UNITED STATES PATENT OFFICE.

CLARENCE M. FLORA, OF OKLAHOMA CITY, OKLAHOMA.

YOKE CONSTRUCTION FOR SHIRTS.

Application filed December 15, 1922. Serial No. 607,128.

To all whom it may concern:

Be it known that CLARENCE M. FLORA, a citizen of the United States of America, residing at Oklahoma City, in the county of 5 Oklahoma and State of Oklahoma, has invented new and useful Improvements in Yoke Constructions for Shirts, of which the following is a specification.

The object of the invention is to provide a 10 neck yoke for garments particularly of the dress, negligee or outer shirt type for men's wear, whereby the neck and shoulder portions thereof are supported and so conformed to the wearer as to afford a snug fit 15 and suspend the weight of the garment from the shoulders rather than from the neck or neck band with the result that a more smooth and neat hanging or draping of the garment may be secured, whereby the pressure 20 upon the neck and throat of the wearer may be relieved, whereby a tendency to draw the neck band downward upon the neck of the wearer is avoided, and whereby the size of the arm hole may be reduced to insure a 25 more snug underarm fit, and at the same time to provide a substantial reinforcement for the back, side and front neck portions of the garment together with the edges of the front opening of the shirt; and with 30 these objects in view the invention consists in a construction and combination of parts of which a preferred embodiment is shown in the accompanying drawings, wherein:

Figure 1 is a view of a neck yoke embodying the invention applied in the operative position to a garment of the shirt type wherein the opening is at the front, the shirt being open to disclose the yoke which is secured to the inner surface of the fabric 40 forming the body of the garment.

Figure 2 is a plan view of the garment, or a view looking downward upon the shoulder portions thereof with the front and back portions spread outward and with the 45 outline of the neck yoke indicated thereon in dotted lines which are distinguishable from those of the seam lines of the body portion of the garment.

Figure 3 is a plan view of the blank forming the neck yoke and indicating the weave lines.

Figure 4 is a view of the blank with the free ends of the yoke and the attached button and buttonhole reinforcing strips carried thereby brought into operative relation as when the garment to which the yoke is

applied is closed and buttoned or otherwise fastened.

The yoke is of neck encircling form constructed from a flat blank preferably of 60 woven material and adapted to be secured to the inner surface of the garment as indicated in Figure 1 wherein the yoke is represented at 10 and the material of the garment at 11, with the free ends of the yoke 65 coinciding with the edges 12 of the opening in the front of the garment, and with the button and buttonhole reinforcing strips 13 carried by and extended in alignment with the free end edges of the yoke and secured 70 to in reinforcing relation with the edges of the opening at the front of the garment.

The device comprises essentially a transverse body member 14 which in this instance is the back member and extends across the 75 back of the garment in rear of the neck opening thereof and side members 15 of curved contour which together with the main transverse member define a neck opening 16, said main and side members merging into 80 and being extended laterally to form shoulder members 17 which extend to the arm holes 18 of the garment and have their terminal edges caught in the armhole seams 19 at the upper sides of the armholes so that 85 said shoulder members extend over and bear upon the shoulders of the wearer.

The side members 15 terminate short of the center line of the yoke to form edges 20 which are disposed (see Figure 3) on outwardly divergent lines, and as the side members of the yoke are of a considerable width measured from the neck opening to the outer peripheries thereof, amounting for example to three or four inches more or less, it is obvious that in order to draw the terminal edges 20 of said side members into meeting or overlapping relation or into parallelism as by the closing of the opening at the front of the garment to which the device is attached it is necessary to contract the outer periphery of the yoke to a greater extent than the inner periphery thereof which constitutes the neck opening, and therefore to cause a downward movement relatively of 95 the shoulder members throughout their lengths and particularly at their outer ends so as to effect a downwardly bearing action of the shoulder members upon the shoulders of the wearer of the garment to thereby support the garment from the shoulder points rather than from the neck and at the same 100 105 110

time cause the intermediate portions of the shoulder members to conform to any irregularity or dipping of the shoulders of the wearer and consequently effecting a snug bearing of the garment upon the shoulders. The button and buttonhole reinforcing strips 13 are extended on outwardly divergent lines corresponding with and forming continuations of the end edges of the side members 15 of the yoke as plainly indicated in Figure 3 and therefore being stitched to the edges of the opening at the front of the garment to which the yoke is applied said reinforcing strips 13 serve to reinforce said opening edges and maintain a proper relation thereof when the yoke has been tensioned at its outer periphery by the drawing together of the outwardly divergent end edges of the yoke due to the closing of the 20 opening at the front of the garment.

From a practical standpoint it is important, however, that the yoke shall be formed with the material constituting the same on a bias and in the construction illustrated the 25 bias line, bisecting the angle formed by the weave lines of the fabric forming the yoke, and indicated by the dotted line *a* in Figure 3 is on a transverse diametral line of the neck opening. The advantage in arranging 30 the fabric forming the yoke in bias relation with the latter is that it affords a yielding quality of the yoke on the lines of strain to which the yoke is subjected in the closing of the opening at the front of the garment which adapts the yoke to more snugly 35 conform to the wearer and insure a downward pressure or tendency of the shoulder members of the yoke which is above described as effecting the support of the garment from the shoulders of the wearer rather than from the neck or by reason of the 40 fitting of the neck opening of the yoke or garment of the neck of the wearer, and when the yoke is constructed as above described with the free end edges of the side members 45 thereof and the reinforcing strips 13 disposed on outwardly divergent lines, radiating from the approximate center of the neck opening, the bias arrangement of the weave 50 is maintained throughout the lengths of said reinforcing strips as well as through the back, shoulder and side members of the yoke proper.

The outer peripheral edges of the side members of the yoke, between the armhole 55 stitches and the stitches which secure the ends of said members to the edges of the opening at the front of the garment are preferably unattached to the body of the garment and are free to conform to the 60 wearer under the tension applied thereto by the closing of the edges of the opening at the front of the garment.

Having described the invention, what is claimed as new and useful is:—

1. As an article of manufacture, a reinforcing lining yoke for the neck portion of a garment having an opening at the front, consisting of a blank of material comprising a body portion to extend across the back 70 of the neck of the garment and conforming to the shoulders thereof, the body portion having a neck opening and front extensions to overlap at the front of the neck, said front extensions merging into reinforcing 75 strips to be secured to the opposite portions of the opening at the front of the garment, thereby reinforcing the button and buttonholes.

2. The combination with a garment provided with an opening at the front, of a reinforcing lining yoke for the neck and shoulder portions of the garment, said lining yoke comprising a body portion secured to and extending across the back of the neck of 80 the garment and secured to and conforming to the shoulders of the garment, said body portion having a neck opening and front extensions merging into reinforcing strips secured to the opposite portions of the opening at the front of the garment, said front extensions with the corresponding portions of the opening in the garment adapted to overlap, whereby the strips may reinforce 85 the button and buttonhole portions of the opening at the front of the garment, said lining yoke being cut on the bias from a blank of material, whereby any strain downward upon the reinforcing strips will be at 90 right angles to a bias line diametral of the neck portion of the yoke bisecting the angle formed by the weave lines of the fabric. 100

In testimony whereof he affixes his signature.

CLARENCE M. FLORA.
